UNITED STATES PATENT OFFICE

ALBERT L. MURRAY, OF AUBURN, INDIANA

DESIGN FOR A RUBBER SOLE FOR SHOES

Application filed March 16, 1931. Serial No. 39,106. Term of patent 7 years.

To all whom it may concern:

Be it known that I, ALBERT L. MURRAY, a citizen of the United States, residing at Auburn, in the county of DeKalb and State of Indiana, have invented a new, original, and ornamental Design for Rubber Soles for Shoes, of which the following is a specification, reference being had to the accompanying drawings, forming part thereof.

Fig. 1 is a plan view of a rubber sole for shoes, showing my new design; and Fig. 2 is a cross-section on line 2—2 of Fig. 1.

I claim:

The ornamental design for a rubber sole for shoes, as shown.

ALBERT L. MURRAY.
